DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

U.S. CL. 134-1

1 Sheet Drawing. 10 Pages Specification

14 15

A diagram showing a horizontal beam 10 resting on a central support 12. At the left end, a weight 4 is suspended from the beam. At the right end, another weight 4 is suspended. A third weight 5 is shown below the beam, positioned between the support and the right end.

Ultrasonic energy is used to create turbulence in a bead of liquid through which is a xerographic element is moved for removing toner particles from the image-bearing surface thereof, thereby preparing the element for further use. The toner particles can be distributed over the surface in the form of an image or as residual toner particles that were not picked up in the course of transferring the image to a receiver sheet. The liquid is continuously circulated and a device is included for filtering out the toner particles that have been removed.
